UNITED STATES PATENT OFFICE.

VICTOR M. BRASCHI, OF MEXICO, MEXICO.

COOKING-STOVE.

No. 856,023.

Specification of Letters Patent.

Patented June 4, 1907.

Application filed August 29, 1905. Serial No. 276,218.

To all whom it may concern:

Be it known that I, VICTOR M. BRASCHI, a citizen of the United States of America, and a resident of the city of Mexico, Mexico, have 5 invented certain new and useful Improvements in Cooking-Stoves, of which the following is a specification, reference being had to the accompanying drawings, forming a part thereof.

10 My invention relates to improvements in cooking stoves, and particularly stoves for the purpose of baking articles by the direct heat from a furnace against the under side of a thin plate supporting them. The stove 15 is particularly designed for cooking tortillas or griddle cakes in this manner.

A stove constructed in accordance with my invention comprises a rotatable tray carrier, a plurality of trays arranged to be supported and carried thereby, and a furnace, from which direct heat is applied to the under side of the trays supported by the carrier. The tray carrier is arranged to support the trays at an angle to the horizontal, 25 and the products of combustion from the furnace are arranged, after impinging upon the under side of the trays, to pass up through a central flue, as will presently be explained in greater detail. The tray carrier is revolved intermittently, whereby a certain time is allowed for baking the article supported by some of the trays, the time being utilized for removing and replacing other trays, and for turning the cakes over on still 30 other trays.

35 My invention also consists in certain details of construction and arrangement of parts, and in a novel form and construction of the furnace portion of the stove, all as will hereinafter more fully appear.

In order that my invention may be fully understood, I will describe in detail, and with reference to the accompanying drawings illustrating same, a cooking stove embodying my invention, and will then point 45 out the novel features in claims.

In the drawings—Figure 1 is a view in central vertical section of a cooking stove embodying my invention; Fig. 2 is a partial 50 top view and a view partially in horizontal section of the same; Fig. 3 is a detail view of a portion of the driving gear; Fig. 4 is a

view in central vertical section taken at right angles to the plane of section of Fig. 1; and Fig. 5 is a view in vertical section taken substantially upon the plane of the line 5—5 of Fig. 1. Fig. 6 is a top view of the stove with the tray carrier removed.

The furnace portion of the stove herein comprises two oppositely arranged combustion chambers 10 10 and intermediate cool spaces 33 33. The outer walls 11 of combustion chambers blend into and are united by a circular wall 12, and the inner walls are connected by an arch 13. Flues 65 14 rise up from the combustion chambers 10, and discharge into a central flue 15. Baffles 16 may also be employed to properly direct the products of combustion, if desired.

70 A carrier 17 is arranged above the furnace portion, being supported upon a shaft 18 mounted concentrically of the stove and driven by suitable gearing. The lower end of the shaft is journaled in a foot bearing 19, 75 and the upper end of the shaft is suitably guided by a bearing 20 in the arch 13. The carrier 17 is preferably of conical form, and comprises a spider 21 directly supported by the shaft 18 at its upper end, and a skeleton 80 framework composed of an upper ring 22, a lower ring 23, connecting bars 24, and spacing pieces 25. A conical open-top hood 26 constitutes the walls of the flue 15, above described and is mounted on the carrier 17 to 85 rotate with it. A stationary hood 27 may conveniently be arranged above the flue 15, said hood being connected with the chimney stack to convey away the products of combustion, as will be well understood.

90 The driving gear for the shaft 18 comprises a bevel gear 28 upon the shaft 18, in mesh with a bevel gear 29 upon a horizontal shaft 30. This horizontal drive shaft carries a spur gear 31, with which a mutilated 95 pinion 32 engages. The relation of the pinion 32 and spur gear 31 to each other is such that continuous rotation of the pinion 32 imparts intermittent movement to the spur gear 31, the carrier being caused to revolve at 100 uniform speed for one quarter of a turn, and then to remain stationary for a certain period.

The carrier is designed to support a suit-

able number of trays 17^a, in the present instance twelve, and each time the carrier comes to rest, three of the trays on one side thereof are at rest over and directly exposed to the heat from one of the combustion chambers 10, and three of the trays upon the other side thereof are at rest over and directly exposed to the heat from the other of the combustion chambers 10. The three trays on either side of the carrier between the combustion chambers are over the cool spaces 33 and free to be handled. At one of these places, then, the trays may be removed, after the cooking is completed, and may be replaced by other trays carrying fresh material to be cooked, while at the opposite side the articles may be conveniently inverted, so that, having cooked on one side while over one of the combustion chambers 10, they may be cooked upon the other side when over the other combustion chamber 10.

It will be noted that the flues are so arranged that all the products of combustion will pass from the flues 14 into the central flue 15 and thence to the hood 27. Thus there will be no waste of heat, nor will the attendant be exposed to the direct heat of the combustion chambers when removing the trays, as would otherwise be the case. By making the carrier 17 generally of a conical form the attendant will be enabled to remove the trays therefrom much more easily than he could if they were supported horizontally, for it is obvious the upper end of the tray will be nearer to the attendant when supported on an incline as shown than it would be if supported horizontally.

What I claim is:

1. In a cooking stove, a furnace portion comprising oppositely arranged combustion chambers and intermediate cool spaces, combined with a rotatable carrier supported above said combustion chambers and cool spaces, said carrier comprising a skeleton frame and a plurality of trays removably supported on the skeleton frame and adapted to carry the articles to be cooked.

2. In a cooking stove, a furnace portion comprising oppositely arranged combustion chambers and intermediate cool spaces, combined with a carrier supported to rotate above the combustion chambers and cool spaces, said carrier comprising a skeleton frame and a plurality of trays removably supported on said frame and adapted to carry the articles to be cooked, and a gearing for imparting intermittent rotary movement to the said carrier.

3. In a cooking stove, a furnace portion comprising two combustion chambers and intermediate cool spaces, combined with a carrier supported to rotate above the combustion chambers and cool spaces, said car-

rier comprising a skeleton frame and a plurality of trays removably supported on the frame, said trays being exposed to the direct heat from the combustion chambers and adapted to carry the articles to be cooked.

4. In a cooking stove, a furnace portion comprising a plurality of combustion chambers and intermediate cool spaces, combined with a carrier supported to rotate above said combustion chambers and cool spaces, said carrier comprising a skeleton frame and a plurality of trays removably supported thereon and adapted to carry the articles to be cooked, and a flue supported upon said carrier to rotate therewith and with which all of said combustion chambers communicate.

5. In a cooking stove, a furnace portion comprising a plurality of combustion chambers and intermediate cool spaces, combined with a carrier supported to rotate above said combustion chambers and cool spaces, said carrier comprising a skeleton frame generally of conical form, and a plurality of trays removably supported on said frame.

6. In a cooking stove, a furnace portion comprising a plurality of combustion chambers and intermediate cool spaces, combined with a carrier supported to rotate above said combustion chambers and cool spaces, said carrier comprising a skeleton frame and a plurality of trays removably supported thereon, said trays being exposed to the direct heat from the combustion chambers, a flue supported by said carrier to rotate therewith and having communication with all of said combustion chambers, and a hood supported above the flue for carrying away the products of combustion.

7. In a stove, the combination with a vertical shaft and a substantially conical carrier frame supported thereby, two combustion chambers arranged one on each side of the said shaft beneath the carrier frame, cool spaces intermediate the combustion chambers, a central flue supported and carried by the said carrier, arranged in open communication with the combustion chambers, removable trays supported by the framework, gearing for intermittently rotating the carrier framework, and a hood for carrying away the products of combustion, arranged above the central flue.

8. In a stove, the combination with a vertical shaft and two combustion chambers arranged one upon either side of the said shaft, a carrier framework carried by the shaft, having tray supporting portions arranged at an angle to the horizontal, whereby the trays will be supported at an angle above the combustion chambers, a central flue carried by the said carrier, said combustion chambers communicating with the said flue, but occu-

pying a portion only of the space around the shaft, whereby intermediate cool spaces are left between the combustion chambers, gearing for imparting intermittent rotary movement to the said shaft, and for holding the same in a rest position for periods intermediate the periods of movement, and a plurality

of removable trays for the said carrier, substantially as set forth.

VICTOR M. BRASCHI.
